DEPOSIT RECEPTACLE FOR NEWSPAPERS
OR THE LIKE

Ernest R. Andis, 5125 Darby Place, Racine, Wis. 53402

Filed May 27, 1968, Ser. No. 12,096

Term of patent 14 years

Int. Cl. D6—01

U.S. Cl. D74—9

FIG. 1 is a perspective view of a deposit receptacle for newspapers or the like;
FIG. 2 is a side view thereof;
FIG. 3 is a top plan view;
FIG. 4 is a view of the side opposite to FIG. 2;
FIG. 5 is a rear view; and
FIG. 6 is a front view thereof.
I claim:

The ornamental design for a deposit receptacle for newspapers or the like, substantially as shown.
